UNITED STATES PATENT OFFICE

LARS O. GRONDAHL, OF PITTSBURGH, AND PAUL N. BOSSART, OF SWISSVALE, PENNSYLVANIA, ASSIGNORS TO THE UNION SWITCH & SIGNAL COMPANY, OF SWISSVALE, PENNSYLVANIA, A CORPORATION OF PENNSYLVANIA

ELECTRIC TRAIN SIGNALING APPARATUS

Application filed November 3, 1930. Serial No. 493,046.

Our invention relates to electric train signaling apparatus of the type disclosed and claimed in application for Letters Patent of the United States filed by L. O. Grondahl, on 5 May 6, 1930, Serial No. 450,135, for electric train signaling systems. One feature of our invention is the arrangement of the apparatus shown in the aforesaid application in such manner that the apparatus will be immune to 10 false operation by foreign fields.

We will describe one form of apparatus embodying our invention, and will then point out the novel features thereof in claims.

The accompanying drawing is a diagrammatic view showing one form of apparatus embodying our invention.

Referring to the drawing, the reference characters 1 and 1^a designate the rails of a railway track, and the reference character 2 20 designates the coupler of a train traveling on such track. The rest of the apparatus is mounted on the train.

The train-carried apparatus comprises two magnetizable cores 3 and 3^a located above the two track rails 1 and 1^a, respectively, and a third core 4 located beneath the coupler 2. Cores 3 and 3^a are provided with windings 5 and 5^a, respectively, and core 4 is provided with a winding 6. The three windings 5, 5^a and 6 are connected in series, and these windings are supplied with alternating current from a generator G when the normally open contact 7—7^b of a manually operable circuit controller C is closed. When this contact is 35 closed, the currents which are induced in the track rails and in the body of the train at any one instant, all flow in the same direction. When the normally closed contact 7—7^a of circuit controller C is closed, the three windings 5, 5^a and 6 are connected in series with a 40

The apparatus as thus far described, is illustrated and described in the application 45 by L. O. Grondahl, referred to above. Assuming that the cores 3, 3^a and 4, are traversed by a changing magnetic field created by current in a distant circuit, it will be observed that voltages will be induced in windings 5, 5^a and 6. In accordance with our

invention, the cores and windings are so designed and arranged that when this occurs, the voltage induced in the winding 6 will be equal and opposite to the sum of the voltages induced in windings 5 and 5^a, so that when contact 7—7^b is closed, substantially no current will be produced by the exterior field in the receiving apparatus comprising signal device F. The apparatus is further so designed that when contact 7—7^b is closed, 60 the voltage produced in the coupler 2 by winding 6 will be the same as the voltage produced in each track rail 1 and 1^a by the associated winding 5 or 5^a.

As here shown, the foregoing result is accomplished by providing windings 5 and 5^a with the same number of turns, providing

winding 6 with twice as many turns as either winding 5 or 5^a, and spacing the cores from the track rails and the coupler so that the voltage induced in the coupler is substantially equal to the voltage induced in each track rail while contact 7—7^b is closed. The same result may be obtained by using the same number of turns in winding 6 as in each winding 5 and 5^a, and increasing the cross-section of the core 4. The desired result may also be obtained by using any desired cross-section with a winding 6. The three windings 5, 5^a and 6 are connected in series, and these windings are supplied with alternating current from a generator G when the normally open contact 7—7^b of a manually operable circuit controller C is closed. When this contact is 35 closed, the currents which are induced in the track rails and in the body of the train at any one instant, all flow in the same direction. When the normally closed contact 7—7^a of circuit controller C is closed, the three windings 5, 5^a and 6 are connected in series with a

As pointed out above, when contact 7—7^b is closed and the apparatus is being used for transmitting signals, the voltage produced in the coupler is the same as that produced in each track rail, and, consequently, the field produced by windings 5, 5^a and 6 at some distance away from the track, such for example, as over an adjacent track, is reduced by the

fact that the field due to winding 6 at the distant point is substantially balanced by the field due to windings 5 and 5^a. Apparatus 95 has the further advantage, therefore, that when it is being used for transmitting signals its effect on the receiving circuit of a train on an adjacent track is substantially zero. 100

In other words, when the apparatus is arranged in accordance with our invention, both its sensitivity to foreign fields and its effect on foreign apparatus are reduced.

5 Although we have herein shown and described only one form of apparatus embodying our invention, it is understood that various changes and modifications may be made therein within the scope of the appended 10 claims without departing from the spirit and scope of our invention.

Having thus described our invention, what we claim is:

1. Train signaling apparatus of the type 15 comprising three windings on a train disposed in inductive relation to the two track rails and a train coupler respectively, and means for at times connecting said windings in series with a source of alternating current 20 and for at other times connecting them in series with a receiving device, said apparatus being characterized by the fact that the winding associated with the coupler has twice as 25 many turns as each of the other two windings, said windings being so spaced from the rails and the coupler that when they are connected with said source of alternating current the electromotive force induced in the coupler is substantially equal to the electromotive force induced in each rail, whereas, 30 the voltage induced in the coupler winding by a changing magnetic field from an outside source is equal and opposite to the sum of the voltages induced by the same field in the other 35 two windings so that when the windings are connected with the receiving device such field has no effect on the device.

2. Train signaling apparatus of the type 40 comprising three windings on a train disposed in inductive relation to the two track rails and a train coupler respectively, and means for at times connecting said windings in series with a source of alternating current, said apparatus being characterized by the 45 fact that the winding associated with the coupler has more turns than either of the other two windings, said windings being so spaced from the rails and the coupler that when they are connected with said source of alternating current the electromotive force induced in the coupler is substantially equal to the electromotive force induced in each rail.

3. Train signaling apparatus of the type 55 comprising three windings on a train mounted on iron cores and disposed in inductive relation to the two track rails and a train coupler respectively, characterized by the 60 fact that the size of the iron core and the number of turns of the winding associated with the coupler is such that the voltage induced therein by a changing magnetic field from an external source is equal and opposite to the sum of the voltages induced by the 65 same field in the other two windings, and by

the further fact that the winding and core associated with the coupler are so spaced from the coupler that a series current in the three windings will induce equal voltages in the same direction in the coupler and in each 70 track rail.

4. Train signaling apparatus of the type 75 comprising three windings on a train mounted on iron cores and disposed in inductive relation to the two track rails and a train coupler respectively, characterized by the fact 80 that the cross-section of the iron core associated with the coupler is such that the voltage produced in the winding on such core by a changing magnetic field from an external source is equal to the sum of the voltages produced in the windings associated with the track rails by the same magnetic field.

In testimony whereof we affix our signatures.

LARS O. GRONDAHL.
PAUL N. BOSSART.
